UNITED STATES PATENT OFFICE.

OMAR H. JEWELL, OF CHICAGO, ILLINOIS.

FILTER.

SPECIFICATION forming part of Letters Patent No. 463,757, dated November 24, 1891.

Application filed December 27, 1890. Serial No. 375,999. (No model.)

To all whom it may concern:

Be it known that I, OMAR H. JEWELL, a citizen of the United States of America, residing at Chicago, in the county of Cook and

5 State of Illinois, have invented certain new and useful Improvements in Filtering Apparatus, of which the following is a specification, reference being had therein to the accompanying drawings.

10 This my invention relates to apparatus for filtering water through woven fabric, felt, or other suitable fibrous material; and it has for its object to provide such an apparatus that with a most simple construction provides a 15 large filtering-surface easily accessible and readily removed and replaced, and so arranged as to be cleaned and washed from time to time by centrifugal force; and with these objects in view my invention consists of the 20 novel devices and combinations of devices hereinafter described and specifically claimed.

In the accompanying drawings, Figure 1 represents a longitudinal vertical section through the center of the apparatus; and Fig. 25 2, an elevation of the interior of the apparatus, one side plate being removed.

Corresponding letters of reference in the several figures of the drawings designate like parts.

30 A denotes the circumferential shell of the casing, provided with an opening in top that is closed by a cover a. Against each side of this casing is fitted and bolted a circular plate B and C, each with a central stuffing-box b and c, through which is placed a tubular shaft D to rotate therein. Upon this shaft D are rigidly mounted two disks E, intermediate of which said shaft is perforated. Over the periphery of these two disks is drawn and 35 secured by screws or any other means a perforated sheet-metal rim F, covering the space between the two disks E, thus forming a circular drum. Around this perforated rim is wound once, twice, or as many times as desirable a band G, of woven fabric or other suitable fibrous material, which is held in position by two rings of rubber H, stretched over the edges thereof. Against the rim edges of each disk E are secured by bolts a series of 45 small lugs h for holding the rubber rings H during the time the band G is removed or replaced over the perforated rim F.

A box I, consisting of a ring with covers to each side, is secured against the center of plate B by means of spider-legs i, so as to 55 clear the stuffing-box b, and the end of shaft D extends into this box I through a stuffing-box j thereof. The opposite end of tubular shaft D being closed by a plug is supported in a journal-box K, secured against plate C, 60 by spider-legs k for clearing stuffing-box c, and upon the overhanging end of this shaft D are mounted a rigid pulley L and a loose pulley M for a driving-belt.

The casing A is provided with legs N for 65 supporting and securing it upon its foundation.

O is the water-feed pipe tapped through the top of plate C and provided with a stop-cock or valve o.

P is the discharge-pipe for the filtered water tapped through the bottom of box I and provided with a stop-cock or valve p.

Q is an air-pipe tapped through the top of box I and provided with stop-cock or valve 75 q, and R is the discharge-pipe tapped through the bottom of plate C and having stop-cock or valve r.

The *modus operandi* of this filtering apparatus is as following, to wit: The valves q 80 and r being closed and the valves o and p opened, the casing A B C will fill with water around the inner drum, which water will filter through the fibrous filtering material G until the inner drum is filled to above its center, when the thus-filtered water will enter the tubular shaft D through the perforations thereof and will escape into box I, and thence through pipe P and valve p it will be conducted to the reservoir for present or future 85 use. After using the filter for awhile the filtering material G will become coated with the impurities from the water filtered and requires cleaning. For this purpose the valves o and p are closed and the valves q and r are 90 opened, when all the water contained in the casing A B C will escape through pipe R and will be replaced by air through pipe Q. Then by applying power, by shifting the driving-belt upon pulley L to set the shaft D and the 100 inner drum mounted thereon in fast rotation, the water contained in such inner drum will be discharged by centrifugal force to pass through the filtering material G in a reversed

direction, thereby loosening and carrying with it all impurities adhering thereto, which will flow off with the water as discharged through pipe R.

5 Whenever the band of filtering fabric is worn and must be renewed this can be accomplished by removing cover *a*, then, while the inner drum is slowly turned, by first shifting the rubber rings *H* to rest upon the lugs *h*, and then by unwinding the band *G*, removing it. In the reversed manner a new band *G* can be replaced in position and then secured by the rings *H*, all through the top opening, without taking the apparatus apart.

15 The air-valve *q* may be attached to the top of casing A B C instead of being placed on box I.

What I claim is—

1. In a filtering apparatus, the combination, with the casing A B C, with pipes O and R, and box I, with pipe P, of tubular shaft D, perforated in its middle and projected through both ends of the casing and into box I, disks

E, mounted upon such shaft D, perforated sheet-metal rim F, covering and connecting 25 both disks E, and a band of fibrous fabric wound over such rim F, all substantially as set forth.

2. In a filtering apparatus, the combination, with the casing A B C, with pipes O and R, 30 and box I, with pipe P, of tubular shaft D, perforated in its middle and projected through both ends of the casing, with one end projecting into box I, and having mounted upon its opposite end a driving-pulley, disks E, mounted upon such shaft D, perforated sheet-metal rim F, covering and connecting both disks E, and a band of fibrous fabric wound over such rim F, all substantially as set forth.

In testimony whereof I affix my signature in 40 presence of two witnesses.

OMAR H. JEWELL.
